DELINTER

William G. Davis, Jr., Glendale, Calif., assignor to Anderson, Clayton & Co., Houston, Tex., a corporation of Delaware

Application May 1, 1950, Serial No. 159,220

12 Claims. (Cl. 19—41)

This invention relates to an improvement in delinters and more particularly is an improvement of the type of delinter described and claimed in the patent to J. B. Ricker, No. 2,310,598 issued February 9, 1943, and re-issued September 5, 1944.

The delinter of J. B. Ricker constituted a considerable advance in the art of delinting, that is removing the lint from the seeds after the ginning operation, in which the motes and trash and minor portions of entrained lint are first removed from the saws by centrifugal force and subsequently the remaining portion of the lint is removed and concurrently therewith the minor portion of the lint entrained with the motes and trash is recaptured and removed with the major portion of the lint, the lint being collected by vacuum means by which air is drawn through a restricted opening between the saws and the enclosed underside thereof.

While the development of J. B. Ricker constituted a considerable advance in the art of delinting and such delinters are presently in widespread use, in operation, although a certain amount of motes and trash are discharged from the saw, an appreciable amount of motes and trash, such as small hull particles with a string of lint attached, are collected with the linters and become entangled and imbedded in the lint in the pneumatic conveyors utilized to transport the lint whereby in the subsequent lint beating operation the removal of such trash and motes is exceedingly difficult. Moreover, it has become increasingly important and necessary to produce a cleaner lint for the chemical industry and lint containing appreciable quantities of small hull particles are objectionable, particularly for use in chemical processes.

Accordingly, it is a prime object of my invention to provide a delinter of the Ricker type in which lint is collected by vacuum means and in which more motes and trash are removed during the delinting operation thereby preventing such motes and trash from becoming imbedded and entangled with the collected linters and thereby providing cleaner lint.

It is a further and major object of my invention to provide a delinter which operates under a negative head of pressure to collect the linters and in which additional motes and trash are removed from both the lint gathering and mote chambers.

It is still a further and more particular object of my invention to provide a lint collecting chamber adapted to be operated by vacuum means having slot means therein adapted to remove motes and trash and adapted to be positioned immediately under the enclosed underside of the saws which is of extremely simple design, is inexpensive and easily manufactured and easily secured to delinters collecting lint from the saws by vacuum means.

It is still a further feature of my invention to provide a collecting chamber operable under vacuum which is extremely simple in design, devoid of complicated, and hence expensive, flues and which may be secured directly under the confined peripheral portion of the saws with-

2

out the use of curved and relatively long flue members extending from the saw chamber to the lint collecting or air chamber.

It is yet a further object to provide an underneath moving attachment adapted to be secured directly under the saw chamber by a flue or neck of minimum length whereby the lighter motes and trash are removed from the lint collecting chamber before the former becomes entangled and imbedded with the latter.

It is still a further feature of my invention to produce a lint substantially devoid of small hull particles and trash which is acceptable to the chemical industry for use in various chemical processes.

Other and further features and objects will be apparent from the following description of my invention taken in connection with the accompanying drawings, where like reference characters refer to like parts throughout the several views, and where

Fig. 1 is a side elevation, partly in section, of a delinter embodying my invention,

Fig. 2 is a fragmentary elevation in section illustrating my lint collecting chamber having a stationary slot to remove light motes and trash,

Fig. 3 is a perspective view of the embodiment of my invention illustrated in Fig. 2 and,

Fig. 4 is similar to Fig. 2 but illustrates a modification thereof.

Referring to the drawings, and particularly Fig. 1, the numeral 10 designates conventional frame and supporting members for the delinter, the latter including the hopper or feeder 12, a roll box 14, a saw cylinder 16, a breast or seed box 18, an overhead moving chamber 20 and a lint collecting or air chamber 22.

The hopper or feeder 12 is of conventional design and has the fluted roll 24 adapted to aid in conveying the seed into the roll box 14.

A float 25 is provided in the roll box 14 which includes the shaft 26 having secured thereto the blades 28. Rotation of the float 25 assists in turning the roll of seed in the roll box 14.

A bank of saws 30 are mounted on the saw shaft 32 disposed in the saw cylinder 16, and a plurality of ribs 34 are disposed between the saws 30 to hold back the seed so that the linters may be stripped from them by means of the saws. While only one saw and rib are shown it is to be understood that a plurality thereof, as is conventional, are utilized. The breast box 18 includes the longitudinally disposed members 36 and 38 which are vertically adjustable by means of the screws 40 (only one being shown) and a lever and linkage, not shown.

The rakes or fingers 27 which project between the saws 30 are rigidly secured to the seed board 29 and are adjustable to control the distance between the rakes 27 and the ribs 34 and thereby regulate or control the discharge of seed into the opening 19.

Disposed at opposite ends of the bank of saws are the end plates 44 which overlap the end saws of the bank and extend rearwardly and downwardly therefrom. The upper front portions of these plates are cut away, as along the lines 46 and 48 to lie behind the breast box member 36 and rearwardly and beneath the saw arbor, the lower portion of the plates along the cutaway line 48 being spaced below the saw blades as to permit subsequent adjustment of the plates relative to the saws. The bottom portions of these plates extend forward into adjacency with the forward edges of the saws and underlie end collars, not shown, holding the saws.

Disposed below the bank of saws is my novel lint collecting or air chamber 22. The lint chamber 22 is of particular configuration and is substantially cylindrical in cross section and is longitudinally disposed below and connected to the saw cylinder 16 by means of the rela-

tively short neck or flue aperture 50. The lint chamber 22 is disposed slightly ahead of a vertical line through the axis of the saw chamber and the forward wall 56 of the flue 50 leads tangentially into the forward portion of and extends around the lower portion of the lint collecting chamber 22, which portions lead tangentially from the lower portion of such chamber to form a lower wall 57 of the neck 52 adapted to be secured to a plurality of lint carrying flues 54. Thus a longitudinal aperture 50 is provided at the upper portion of the chamber 22 and a longitudinal aperture 58 is provided at the lower and rearward portion thereof and at substantially right angles to the aperture 50. Thus an air passage is provided extending to the underside of the saws 30 which provides a passage through which linters from the saws may pass into the lint carrying flue 54. A more detailed description of my novel lint collecting chamber is given later herein.

The underside of the saws are peripherally enclosed by the arcuately extending rearward 60 and forward 62 wing plates extending from the walls of the aperture 50. The rearward wing plate 60 terminates in the downwardly and rearwardly extending wing plate 64, which defines the lower opening of the upper mote chamber 20, and the forward wing plate rests on the longitudinal member 38. In order that the saws may be sharpened or replaced and the wing plates 60 and 62 may closely conform at all times to the peripheries thereof, the wing plates are adjustably positioned as by the hinges 66, 68, the wing nuts 70, the lever and linkage 72 and the vertically adjustable supporting tie bolts 76. No more details of the adjustable features of the wing plates confining the lower portions of the saws, the mote chamber 20 and the adjustable features of the linting chamber 22 are given inasmuch as they form no part of my invention and are adequately set forth in the above mentioned patent to J. B. Ricker.

Referring now more particularly to Figs. 2 and 3, my novel linting chamber 22 is substantially circular in cross section and has the slot 80 located at the forward point of the longitudinal aperture 58 disposed rearwardly in the chamber 22, which slot extends longitudinally across the aperture 58. I have found that the longitudinal aperture 80 may be satisfactorily fabricated by removing approximately 2 inches of the lower wall 57 of the flue aperture 52 and bending the removed portion at its central portion until the lip or baffle 82 extends approximately $\frac{5}{16}$ of an inch above the level of the lower portion 57 of the flue aperture 52. I do not intend to be limited to these dimensions, but they have proved satisfactory in use. I believe it to be preferable, however, to have a relatively sharp angle of the lip or baffle 82 with the wall 57 whereby air drawn into the chamber 22 through the slot will be generally in a direction opposite to that of the air drawn therethrough. Conventional securing means, such as a plurality of spacer clips 84 rigidly secures the upwardly and inwardly extending lip 82 in position. The upper portion of the lip or baffle 82 should be buffered and polished until smooth in order that no lint will be caught and retained thereby. Thus the slot 80 permits air to be drawn into the delinting chamber 22 which prevents the lint from escaping therethrough but light motes and trash, such as seed hulls and the like, are thrown therethrough. While the slot 80 may be disposed in any portion of the lower wall 57 of the lint gathering or air chamber 22 it is preferable to place the slot at the bottom and rearward portion thereof to prevent mote and trash from bypassing the slot, and it is particularly advantageous to place the slot directly behind the enlarged portion of the chamber 22 wherein circular air currents are set up and air is drawn directly into the rearward portion of the enlarged chamber 22 thereby permitting motes and trash to be thrown against the outer wall 57 by centrifugal force thereby separating the motes and trash from the lint, the motes and trash flowing along the bottom mem-

ber 57 with sufficient momentum to force them through the slot against the force of the incoming air.

Fig. 4 illustrates a modification of my development wherein the only change is that the slot 80 is made adjustable by means of the hinge 86, the lip or baffle 82 being resiliently and yieldingly urged downwardly by the spring 83 against the adjusting means or screw assembly 88. The adjustable feature has some additional advantages over the rigid slot, such as during cleaning operations of the machine and in working extremely trashy seed where it is advantageous to vary the opening of the slot, and the like; however, after the desired angle is determined by pilot tests for the particular unit and seed to be worked, the rigid slot is believed to be as advantageous as the adjustable slot.

In operation cottonseed from the ginning operation is deposited into the feeder or hopper 12 and passed to the roll chamber 14. The lint is stripped from the seed by virtue of the bank of saws 30, the ribs or breastplates 34 holding back the seed so that the lint might be removed therefrom. The seed passes out of the opening 19 which provides one intake for air being drawn into the delinter by means of suitable vacuum means (not shown) disposed at the end of the lint conveying flue 54.

The heavier motes and trash are thrown into the mote chamber 20 by the centrifugal action of the saws 30 and the air withdrawn through the confined passageway established by the wing extensions 60 and 62 in connection with the saws is drawn through the longitudinal flue aperture 50 into the lint or air chamber 22 and from the lint collecting or air chamber 22 into the lint flues 54, thus materially assisting the major portion of the lint to follow around with the saws and into the lint collecting chamber. The enlarged chamber 22 permits a swirling or whirling action which tends to throw the trash outwardly by centrifugal force and air sucked into the chamber through the longitudinal slot 80 is directed into the air current passing through the air chamber 22 whereby the trash not removed in the overhead moting chamber is thrown out of the slot by momentum against the force of the incoming air. Thus the lighter motes, such as hull particles with a string of lint attached thereto are removed from the lint chamber by means of a swirling or whirling action separating the motes from the lint by centrifugal force whereby the motes are thrown against the lower wall 57, the momentum thereof throwing the trash out of the slot against the force of the incoming air which aids in retaining the lint in the air chamber 22 for passage into the lint conveying flue 54. It should be noted that the forward 56 and lower wall members 57 of the chamber 22 are preferably smooth and the walls are tangential thereto.

Concurrently air is drawn in through the channelway established by the extension or wing plate 62 in a direction opposed to the rotation of the saws which successfully checks and prevents, to a large extent at least, a carrying of any lint by the saws beyond the channelway leading downwardly into the air or lint collecting chamber 22. It seems manifest that the minor portion of lint entrained in or thrown by centrifugal action of the saws with the motes and trash in the mote chamber 20 will be drawn by the air current along the passageway formed by the wing 60 and the lower portion of the saw bank 30, thus recapturing a substantial amount of the lint thrown into the mote chamber 20.

In actual practice it has been found that a delinter as above described without the slot 80 removes four pounds of motes or trash per ton of normal seed worked when operated under normal conditions, such as 0.7 inch of water pressure measured at the back portion of the device drawing 1,350 C. F. M. of air at a velocity of 2500 ft. per minute therethrough. It has been found that the delinter without the slot 80 may be operated at a negative pressure of from 0.5 to 0.7 inch of water.

In operating a delinter under the same set of condi-

tions, that is 0.7 inch of water pressure measured at the back of the device and the system drawing 1350 C. F. M. of air at a velocity of 2500 ft. per minute therethrough, it has been found that the underneath slot, that is slot 30 in the delinting chamber 22 recovered 2½ pounds of light motes and trash per ton of seed worked and that surprisingly the overhead removal of motes and trash in the mote chamber 20 was increased from 4 to 5½ pounds per ton of seed worked. Manifestly, much cleaner lint is passed to the subsequent lint beating operation thereby simplifying the entire procedure inasmuch as very little trash and motes, if any, remain in the lint and become embedded and entangled therein while conveying the lint thereby avoiding difficult lint beating operations. While I do not wish to be bound by any theory of operation it appears that by bleeding in air in the slot 30 in the lint gathering chamber 22 that the velocity of the system is still maintained but at the same time there is less volume and velocity of air drawn through the saw chamber thereby permitting a larger volume of motes and trash to be thrown into the mote chamber 20 and by properly adjusting the opening of the latter it is still possible to recapture a substantial portion of the lint entrained and thrown with the motes into the mote chamber 20 by the centrifugal action of the saws 30.

It is exceedingly important and critical to place the slot means in the lint gathering or air chamber, and preferably at the rear and lower part thereof in order that there will be no by-passing of motes and trash and full advantage of the swirling or whirling action is obtained. Thus it is manifest that the exact location of the slot is of utmost importance in recovering an optimum amount of light motes and trash from the linting chamber as well as increasing the recovery of the moting chamber proper.

It will be understood so long as the slot is located in an enlarged lint gathering chamber, such as 22, connected by a substantially straight short neck that numerous changes may be made in the details of construction thereof and that the slot means may be either stationary or adjustable as desired. It is necessary that the incoming air through the slot be directed into the air current flowing through the air chamber 22 in order that the motes and trash may be thrown through the slot means by a combination of centrifugal force and momentum against the force of the incoming air, thus preventing the lint from being thrown out through the slot means and thereby conveying the lint to the lint conveying flues 54 for subsequent operations.

I claim:

1. In a delinter employing a bank of delinter saws and vacuum means to collect lint therefrom, a mote chamber disposed rearwardly of said bank of saws having front and rear openings, the lower edge of its front opening being disposed at approximately shaft level of said bank of saws whereby motes and trash and minor portions of entrained lint are thrown into such mote chamber by centrifugal force of the saws, and having wall means peripherally enclosing the nether side of said bank of saws and defining a confined passageway substantially conforming to the periphery of such saws adapted to receive lint from such saws and entrained lint from the mote chamber, the improvement of a lint-gathering chamber disposed immediately under said bank of saws and communicating with such passageway, such lint-gathering chamber being substantially cylindrical, relatively short conduits tangentially connected to forward and underside portions of said lint-gathering chamber and adapted to establish communication with such confined passageway and to a lint-conveying flue, and slot means longitudinally disposed in the lower portion of such lint-gathering chamber whereby air being drawn through such delinter by such vacuum means will draw lint into such lint-gathering chamber, the air being drawn through

5 such lint-gathering chamber being peripherally whirled whereby motes and trash are separated from the lint by centrifugal force and the motes and trash are thrown out of such lint-gathering chamber through such slot means.

2. The delinter of claim 1 wherein the slot means include a rigid baffle extending into the direction of air flow in the lint collecting chamber.

3. The delinter of claim 1 wherein the slot means include an adjustable baffle extending into the direction of air flow in the lint collecting chamber.

4. The delinter of claim 1 wherein the slot means is located in the lower and rearward portion of the lint collecting chamber.

5. In a delinter employing a bank of delinter saws and vacuum means to collect lint therefrom, a mote chamber disposed rearwardly of said bank of saws having front and rear openings, the lower edge of its front opening being disposed at approximately shaft level of said bank of saws whereby motes and trash and minor portions of entrained lint are thrown into such mote chamber by centrifugal force of the saws, and having wall means peripherally enclosing the netherside of said bank of saws and defining a confined passageway substantially conforming to the periphery of such saws adapted to receive lint from such saws and entrained lint from the mote chamber, the improvement of an underneath moting chamber adapted to be connected to the underside of the delinter and establish communication with such confined passageway comprising, a lint gathering chamber substantially cylindrical, relatively short conduits tangentially connected to the forward and underside portions of said chamber and adapted to establish communication with such confined passageway and to a lint conveying flue, and slot means longitudinally disposed in the lower portion of such chamber whereby air being drawn through such delinter by such vacuum means will draw lint into such lint gathering chamber, the air being drawn through such lint gathering chamber being peripherally whirled whereby motes and trash are separated from the lint by centrifugal force and the motes and trash are thrown out of such linting chamber through such slot means.

6. The underneath moting chamber of claim 5 wherein the slot means include a rigid baffle extending into the direction of air flow through the lint gathering chamber.

7. The underneath moting chamber of claim 5 wherein the slot means include an adjustable baffle extending into the direction of air flow through the lint gathering attachment.

8. The underneath moting chamber of claim 5 wherein the slot means is located in the lower and rearward portion of the lint gathering chamber leading tangentially to such lint conveying flue.

9. An underneath moting attachment adapted to be secured to the underside of a delinter operable to collect lint by vacuum means comprising, a substantially cylindrical lint-gathering chamber, a relatively short inlet conduit tangentially extending from a side wall of said chamber at substantially a right angle to the axis of the chamber adapted to establish communication with the underside of a saw cylinder of the delinter, a relatively short outlet conduit extending from the side wall of said chamber at substantially a right angle to the axis of the chamber and adapted to establish communication with a lint-carrying flue, a wall of the inlet conduit and the outlet conduit merging with the side wall to form a smoothly continuous, generally L-shaped wall with a curved intermediate portion, viewed in cross-section, said L-shaped wall having a floor defined by the intermediate portion and the wall of the outlet conduit, and slot means longitudinally disposed in the floor so that air drawn from the saw cylinder through such lint-gathering chamber is peripherally whirled whereby motes and trash are separated from the lint by centrifugal

force and the motes and trash are thrown out of the lint-gathering chamber through the slot means and air drawn through the slot means assists in conveying the lint to the lint-carrying flue.

10. The underneath moting attachment of claim 9 5 wherein the slot means include a rigid baffle extending into the direction of air flow through the lint gathering chamber.

11. The underneath moting attachment of claim 9 10 wherein the slot means include an adjustable baffle extending into the direction of air flow through the lint gathering attachment.

12. The underneath moting attachment of claim 9

where the slot means is located in the floor adjacent the outlet conduit.
